(57) CLAIM

() Term: 14 Years

The ornamental design for a combination tablet notebook computer, as shown and described.

(21) Appl. No.: 29/134,188

DESCRIPTION

(22) Filed: Dec. 15, 2000

FIG. 1 is a perspective view of the combination tablet notebook computer of the instant invention showing the tablet side thereof;

(51) LOC (7) Cl. 14-02

FIG. 2 is a front view of the combination tablet notebook computer of the instant invention;

(52) U.S. Cl. D14/345; D14/322; D14/341

FIG. 3 is a top view of the combination tablet notebook computer of the subject invention;

(58) Field of Search D14/341, 345,

FIG. 4 is a rear view of the combination tablet notebook computer of the subject invention;

D14/315, 322, 336; D18/1, 2, 7; D19/26,

59, 60; 235/145 A, 145 R; 341/22, 23;

345/104, 156, 168–169, 173; 361/680–686;

349/12

FIG. 5 is a left side view of the combination tablet notebook computer of the instant invention with the right side view being a mirror image thereof; and,

FIG. 6 is a bottom view of the combination tablet notebook computer of the instant invention.

The broken lines are shown in the views for illustrative purposes only and form no part of the claimed design.
